UNITED STATES PATENT OFFICE.

EDWARD G. DORCHESTER, OF GENEVA, NEW YORK.

TIMING INSTRUMENT.

SPECIFICATION forming part of Letters Patent No. 580,573, dated April 13, 1897.

Application filed May 27, 1896. Serial No. 593,240. (No model.)

To all whom it may concern.

Be it known that I, EDWARD G. DORCHESTER, a citizen of the United States, and a resident of Geneva, in the county of Ontario, in the State of New York, have invented new and useful Improvements in Timing Instruments, of which the following, taken in connection with the accompanying drawings, is a full, clear, and exact description.

10 This invention relates to the class of timing instruments which includes the instrument shown in Letters Patent No. 550,414, granted to me November 26, 1895.

The instrument is provided with a dial and hands or indicators similar to a watch and actuated by the rotation of one of the wheels of the bicycle and is designed to be used in connection with a clock or watch with the time of which the movements of the hands or indicators of the instrument are to be compared to ascertain if the bicycle is traveling a predetermined distance within a certain period, as hereinafter more fully described. Said clock or watch may be carried on the person riding a bicycle.

30 My present invention consists in an improved construction and combination of the component parts of the mechanisms of a timing instrument, as hereinafter described, and set forth in the claims.

In the annexed drawings, Figure 1 is a perspective view of that part of a bicycle to which my speed-indicator is applied. Fig. 2 is a front view of the same. Fig. 3 is an enlarged detached perspective view of said indicator. Figs. 4 and 5 are vertical transverse sectional views of the inclosing case, showing the internal mechanisms. Fig. 6 is a horizontal transverse section on line Z Z in Fig. 4. Fig. 40 7 is a horizontal transverse section on line O O in Fig. 5. All of said sectional views are taken in the directions indicated by the arrows. Fig. 8 is a horizontal transverse section on line U U in Fig. 4. Fig. 9 is a horizontal transverse section on line V V in Fig. 5. Fig. 10 is a longitudinal section on line W W in Fig. 7. Fig. 11 is an enlarged side view of the attachment of the instrument-pulsating spurs to the wheel of the bicycle. Fig. 12 is a longitudinal section on line T T in Fig. 11, and Fig. 13 is a perspective detail view of the skeleton supporting-frame of the inclosing case of the instrument.

Similar letters of reference indicate corresponding parts.

A denotes the inclosing case of the speed-indicating instrument. This case consists, essentially, of a cylindrical body sustained revolubly on the exterior of a skeleton frame consisting of the two end plates A² and B², which are tied to each other by staves C C of suitable spring metal fastened at one end to the bottom plate A² and provided at the opposite or free ends with notches C' C', as shown in Fig. 13 of the drawings. The top plate B² of the case is provided with notches C² of such dimensions as to closely fit therein the narrowed notched portions of the staves, which are caused to enter said notches by bending the free ends of the staves outward and then allowing them to spring into the notches C². The staves thus become securely interlocked with the top plate. The cylindrical body of the case is sustained revolubly on the exterior of the staves and prevented from moving longitudinally by the projection of the margin of the bottom plate A² and by the bottom edge of a ring B', attached to the top plate B². The inner side of the cylindrical body A is provided with spiral grooves a' a' for the purpose hereinafter explained.

Longitudinally through the center or axis of the case A extends the shaft a, as hereinbefore stated, which shaft has fastened to it a pointer b, which in the rotation of the shaft traverses the dial B.

To the shaft a is rigidly secured a cone of gears D or a series of gear-wheels of successively-increasing diameters, each individual gear of which is separated from the adjacent companion gear by interposed disks c c, each of which projects with its peripheral edge slightly beyond the face of the adjacent larger gear.

Parallel with the shaft a is a gear-wheel d, which is of a length equal to the height of the cone of gears D and is of a uniform diameter throughout its length and pivoted to the end plate of the case A. The gear d transmits motion to the shaft a by means of an intermediate pinion e, which is sustained movably in two directions—viz., in a line parallel with the shaft a and radially toward and from said shaft—so as to allow it to transmit motion from the gear d to the cone of gears D of dif-

ferent diameters and in different planes. By changing the position of the pinion e to engage a larger or smaller gear of the cone D the speed of the rotation of the latter is increased or diminished proportionately. For supporting the pinion e adjustably in its position, as aforesaid, I prefer to pivot it to the free end of an arm e' , pivoted to a plate f , which is provided with outwardly-projecting lugs f' , by which it rides in the spiral grooves a' in the inner side of the case A , as hereinbefore described. Two of the staves C C , abutting against opposite sides of two of the lugs f' , serve to prevent the plate from turning with the cylinder of the case in adjusting the plate, as hereinafter described. Said staves also serve to guide the plate in its vertical movement. By turning the said case about its axis the said spiral grooves cause the plate f to move lengthwise of the case.

In order to allow the pinion e to be held out of engagement with the cone of gears D during the aforesaid adjustment of its supporting-plate f , I pivot to the ends of the case A a post g , which extends through the case parallel to the axis thereof and is provided with a longitudinal groove g' , which engages a correspondingly-shaped heel f^2 on the plate f back of the pivot thereof, as more clearly shown in Fig. 6 of the drawings. One end of the post g protrudes from the end of the case A and is squared, as shown at g^2 , or otherwise suitably shaped for the application of a suitable instrument by which to turn said plate, so as to cause it to swing the plate f from the cone of gears D . A suitable spring h serves to automatically force the plate f toward the cone of gears.

To limit the inward movement of the free end of the arm e' , so as to prevent the pinion e from jamming or excessive engagement with the gears of the cone D , I form said arm with a guard e^2 , consisting of an enlargement of the width of the arm at the axis of the pinion e , which bears on one of the disks c , as shown in Fig. 6 of the drawings.

The gear d receives motion by means of suitable intermediate gears from a shaft i , which is pivoted to the case and has one end protruding therefrom and has fastened to said end a star-wheel I or other suitable device to be actuated by the wheel V of the bicycle. When the said star-wheel is employed, I attach to the spokes of the wheel V a suitable spur j , which, during the rotation of said wheel, strikes one of the arms of the star-wheel and thereby imparts an impulse to the shaft i , which, by means of the aforesaid intermediate gears, transmits motion to the gear-wheel d .

In order to adapt the instrument to be actuated so as to indicate a greater or less speed required to be traveled by the bicycle within a predetermined period, I attach to the wheel V a plate or strap J , provided with two lugs or spurs j and j' , one or both of which are adjustable to and from lateral pro-

jecting positions. Said adjustability may be attained in various ways, one of which is illustrated in Figs. 11 and 12 of the drawings, and consists of a section of the plate J being hinged to the main portion of said plate, so as to allow it to turn at right angles thereto, and provided with a suitable brace j'' to sustain it in its projecting position. Suitable latches k' are connected to the plate J for locking the said hinged section or lug in its required position.

For transmitting motion from the shaft i to the wheel d with minimum jars to the mechanisms I prefer to employ the worm-gear i' , fastened to the shaft i and meshing with a pinion k , fastened to a shaft which is disposed at right angles to the shaft i and pivoted to suitable supports l l , sustained in the case, as shown in Figs. 4 and 7 of the drawings. To the shaft of the pinion k is secured a worm-wheel l' , which meshes with a pinion m , attached to a shaft m' at right angles to the shaft of the pinion k , and has fastened to it a worm-gear n , meshing with the gear-wheel d , which latter wheel is axially at right angles to the shaft m' and parallel with the shaft of the cone of gears D , as hereinbefore described. The pointer b on the shaft a of said cone of gears is to indicate on the dial B the minutes of time consumed in the travel of the bicycle, and by comparing the time thus indicated with the time indicated on the watch the rider ascertains if the bicycle travels at the desired speed.

For indicating the hours I fasten to the shaft a of the cone of gears a pinion n' , which meshes with a gear-wheel o , pivoted to suitable supports secured to the interior of the case. The shaft of this wheel projects through the top plate or dial of the case A and has fastened to its upper end a pinion o' , which meshes with a gear-wheel o^2 , mounted loosely on the shaft of the cone of gears D . The top of the wheel o^2 has marked on it or fastened to it a pointer p , which indicates the hours on the dial B .

To allow the hands or pointers b and p to be set to correspond to the time indicated on the watch at the time the rider of the bicycle starts on his trip, I make the shaft a of the cone of gears D of sufficient length to protrude from the end of the case, preferably from the lower end thereof, as shown, and square said end, as shown at a' , or otherwise shape it for the application of a key by which to turn said shaft.

The described instrument is made adjustable to regulate the movement of the hands or pointers b and p to greater or less speed during the travel of the bicycle over a certain distance. This adjustment is effected by turning the cylindrical body of the case A about its axis, for which purpose I serrate or otherwise roughen the exterior of the lower portion of the case A , as shown at R , which affords a good hold for one hand of the operator to turn the cylindrical body while holding the end of

the case by the other hand of the operator. By turning said case as aforesaid the spiral grooves a' thereof cause the plate f , hereinbefore described, to move lengthwise of the case 5 and in a line parallel with the shaft a of the cone of gears D . During this operation the shaft g is to be turned so as to cause it to swing the arm e' outward and hold the pinion e out of contact with the cone of gears, as 10 hereinbefore described. After the arm e' has been thus adjusted to bring the pinion e opposite the desired gear of the cone said arm is allowed to throw the pinion into engagement with the gear. Inasmuch as the pinion 15 e serves to transmit motion to the cone of gears D it is obvious that the shifting of said pinion from one to another of the gears of the cone changes the speed of transmission.

To lock the cylindrical body of the case to 20 the ends thereof, so as to retain the pinion e in engagement with the desired sized gear of the cone D , I provide the top edge of the cylindrical body of the case A with a series of notches r , one for each of the successively 25 smaller gears of the cone D . To the under side of the top plate of the case I connect a sliding bolt r' in proximity to the side of the upper end of the shaft g , to which is secured a radially-projecting pin s , the free end of 30 which engages a notch s' in the side edge of the bolt, as shown in Fig. 7 of the drawings.

The outer end of the bolt r' is formed with 35 a tongue r^2 , which passes through one of the notches r and enters a hole in a lip q , which is secured to and depends from the exterior 40 of the ring B' , attached to the top plate B^2 of the case, as shown in Fig. 5 of the drawings.

A spring q' , secured to the under side of the top plate B^2 and pressing against the inner 45 end of the bolt, forces the latter outward and holds the same in engagement with the notch r . In turning the shaft g to throw the pinion e out of engagement with the cone of gears D preparatory to adjusting the instrument for 50 indicating different speeds, as hereinbefore described, the pin s on said shaft pushes the bolt r' inward, so as to withdraw the tongue r^2 thereof from both the lip q and notch r , and thus the cylindrical body of the case A is unlocked from its before-described supporting-frame and allowed to be turned thereon to its 55 desired position, where it is then locked by the turning of the shaft g to throw the pinion e into engagement with the cone of gears D , in which operation the pin s on said shaft releases the bolt r' and allows the spring q' to force said bolt outward to engage the notch r and hole in the lip q .

A stop t' is attached to the exterior of the 60 cylindrical body of the case A in proper position to come in contact with the lip q , and thereby limit the rotation of said cylindrical body.

The instrument herein illustrated is arranged to be adjustable for speeds of seven, 65 eight, nine, ten, eleven, twelve, thirteen, fourteen, and fifteen miles per hour by using both

spurs j on the wheel V . By employing only one of said spurs it is obvious that the bicycle must be propelled double the aforesaid speed 70 in order to move the hands or pointers p of the instrument in unison with the hour and minute hands of the watch or clock.

The top of the case is provided with a crystal or transparent glass disk t , which is secured to the ring B' , fastened to the top plate 75 B^2 of the case.

The bottom plate A^2 of the case has projecting from it the bifurcated shank A' , by which to secure it in any suitable manner to 80 the axle of the wheel V .

What I claim as my invention is—

1. A speed-indicator consisting of an inclosing case provided with a dial, a shaft extending through said case and having affixed 85 to it a pointer traversing said dial, a plurality of gears of different diameters secured to said shaft, an axially-prolonged gear parallel with said shaft, a revolable spiral axially parallel with the aforesaid shaft, a plate riding on the 90 helices of the spiral, vertical guides preventing said plate from turning with the spiral, a pinion supported on said plate adjustably to transmit motion from the prolonged gear to either of the aforesaid different-sized gears, 95 a pulsator actuated by the wheel to be timed, and mechanisms transmitting motion from said pulsator to the prolonged gear as set forth.

2. In a speed-indicator, the combination of 100 an inclosing case having a cylindrical body revoluble on the ends of the case, a dial on one end of said case, a shaft passing through the center of the dial and case, a plurality of gears of different diameters secured to said 105 shaft, a pointer on said shaft traversing the dial, spiral grooves in the inner side of the cylindrical body, a plate riding in said grooves, vertical guides preventing said plate from turning with the cylindrical body, a 110 vertical shaft passing through the plate and provided with a longitudinal groove, an arm pivoted to said plate and formed with a heel engaging said groove to adjust the arm by the turning of the shaft, a pinion pivoted to 115 the free end of said arm to engage or release either of the aforesaid different-sized gears, 120 an axially-prolonged gear engaging said adjustable pinion, a pulsator actuated by the wheel to be timed, and mechanisms transmitting motion from said pulsator to the prolonged gear, as set forth.

3. In a speed-indicator, the combination of 125 an inclosing case having a cylindrical body revoluble on the ends of the case, a dial on one end of the case, a shaft passing through the center of said dial and case, a pointer on the end of said shaft traversing the dial, a plurality of gears of different diameters secured to said shaft, a spiral guide on the inner side of the aforesaid revoluble body, a 130 plate riding on said guide, vertical guides restraining revoluble motion of the plate, a pinion supported adjustably on said plate to

engage either of the aforesaid different-sized gears, an axially-prolonged gear engaging said pinion, a pulsator-shaft actuated by the wheel to be timed, a worm-gear on said pulsator-shaft, and intermediate gears transmitting motion from said worm-gear to the aforesaid prolonged gear to relieve the instrument from excessive jars in the transmission of motion, as set forth.

10 4. The combination with the shaft *a* and gear *d* axially parallel with said shaft, of the cone of gears *D*, interposed disks *c c'*, arm *e'* movable toward and from said cone and formed with the guard *e* and the pinion *e* pivoted to said arm and transmitting motion from the gear *d* to the cone of gears, as set forth.

5 5. The combination of the case *A* having its cylindrical body revoluble on the end portions of the case, a cone of gears in said case, 20 a gear-wheel axially prolonged and parallel with the axis of the cone, a spiral way on the inner side of the revoluble body, a plate riding on said spiral way and restrained from rotating with the aforesaid body to cause said 25 plate to be moved lengthwise of the cone by the rotation of said body, a pinion supported on said plate adjustably to transmit motion from the prolonged gear to either of the different-sized gears of the cone, and means for 30 locking the revoluble body in its adjusted position.

6. The combination of the case *A* having its cylindrical body revoluble on the end portions of the case and provided with a spiral 35 way on its inner side, a shaft extending through the case parallel with the axis thereof, a plurality of gears of different diameters secured to said shaft, a plate riding on the helices of the spiral way and restrained from 40 rotating with the revoluble body, an axially-prolonged gear parallel with the aforesaid shaft, a pinion supported on the aforesaid plate adjustably to transmit motion from the prolonged gear to either of the aforesaid different-sized gears, a series of bolt-holes in the 45 wall of the cylindrical body and arranged to indicate the degree of rotation required of said body to carry the adjustable pinion to the desired different-sized gear, and a bolt 50 locking the said body in its adjusted position, as set forth.

7. The combination of the case *A* having its cylindrical body revoluble on the end portions of the case and provided on its inner side with a spiral groove, a dial on the end 55 of the case, a shaft passing through the centers of the dial and case, a pointer on the end of said shaft, a cone of gears secured to said shaft inside of the case, an axially-prolonged gear parallel with said shaft, a pulsator actuated by the wheel to be timed, mechanisms transmitting motion from said pulsator to the prolonged gear, a plate riding in the helices of the aforesaid groove and restrained from rotating with the body of the case, an arm 60 pivoted to said plate, a pinion pivoted to the free end of said arm to transmit motion from the prolonged gear to either of the different gears of the cone, a post passing through the aforesaid plate and pivoted to the end plates 65 of the case and engaging the pivoted arm to adjust the same, a series of bolt-holes in the wall of the revoluble body, a bolt entering said holes to lock said body, and a pin on the aforesaid pivoted post engaging the bolt to 70 withdraw the same from its interlocked position simultaneously with the adjustment of the pivoted arm to throw the pinion thereof out of engagement with the cone of gears, as 75 set forth.

8. The case *A* composed of the end plates *B²* and *A²*, staves *C C'* tying said plates together, and a cylindrical body sustained revolvably on the exterior of the said staves between the end plates of the case, as set forth. 85

9. In combination with the timing instrument and vehicle-wheel to be timed, a star-wheel attached to the protruding end of the pulsator-shaft of said instrument, a plate secured to the vehicle-wheel, and a plurality of 90 spurs connected to said plate adjustably into and out of position to come in contact with the star-wheel to impart more or less impulses to the timing instrument during each revolution of the vehicle-wheel.

In testimony whereof I have hereunto signed my name this 22d day of April, 1896.
